LIBANUS M. TODD, OF ROCHESTER, NEW YORK, ASSIGNOR TO TODD PROTECTOGRAPH COMPANY, OF ROCHESTER, NEW YORK, A CORPORATION OF NEW YORK.

CHECK-PROTECTOR.

1,335,207.

Specification of Letters Patent. Patented Mar. 30, 1920.

Application filed April 8, 1916. Serial No. 89,913.

To all whom it may concern:

Be it known that I, LIBANUS M. Todd, of Rochester, in the county of Monroe and State of New York, have invented certain new and useful Improvements in Check-Protectors; and I do hereby declare the following to be a full, clear, and exact description of the same, such as will enable any person skilled in the art to which the invention appertains to make and use the same.

This invention relates to printing machines, and more particularly to that variety of such apparatus which is adapted for printing upon small forms of paper such as checks, drafts and other commercial instruments. The present embodiment of the invention is especially suitable for writing in the monetary value for which a check or similar instrument is drawn, so as to provide an indelible inscription of the amount, thereby protecting the instrument against fraudulent alteration.

One object of the invention is to provide a machine of this type of a simple and efficient construction adapted for convenient and rapid operation to impress the work. To this end the machine is so constructed that the types for printing the whole inscription may be conveniently selected and brought to printing position, so that the inscription may then be quickly and completely printed by a single impressing operation of the machine. The machine is thus particularly useful where a number of instruments are to be impressed with the same inscription, as, for instance, in printing so-called payroll checks.

Another object is to provide a machine of this type with a work supporting table conveniently arranged for the insertion and removal of the work and constructed to be automatically moved during the printing operation to carry the work to and from position to receive the printing impression, as well as to provide means for automatically clamping the check upon the table during the movement of the latter.

Another object is to provide a machine having a simple and efficient means for automatically inking the types brought to printing position prior to each impression.

These and other objects and advantages will be made clear by the following de-

tailed description of one form of the invention illustrated in the accompanying drawings in which:

Figure 1 is a top plan view of the machine.

Fig. 2 is a sectional elevation of the machine taken on the line 2—2 of Fig. 1.

Fig. 3 is a sectional elevation taken substantially on the line 3—3 of Fig. 2.

Fig. 4 is a sectional elevation taken on the line 4—4 of Fig. 3, showing the mechanism in normal position.

Fig. 5 is a similar view showing the positions of the parts during the printing impression.

The present embodiment of the invention comprises a machine adapted for printing monetary values upon checks and similar instruments, and preferably having types for writing a series of words expressing amounts adapted to be used in selected combinations for writing a wide range of monetary values. Words are preferred for this purpose, rather than figures, because they form an impression which is more difficult to alter. These types are conveniently arranged in a plurality of series, each series being preferably carried on an adjustable support, or bar, which is longitudinally slidable in a horizontal plane so that any type of each series may be brought to printing position in combination with one or more types of other series for printing a complete expression of any desired amount. The platen is movably supported below the type supporting members and mechanism is provided for raising and lowering the platen to press the paper into printing contact with the type.

In combination with a machine of this description there is preferably provided a movable work supporting table which in normal position extends without the casing of the machine and is adapted by means of an actuating connection with the operating lever for the printing couple to be moved toward and from the latter during the printing impression to carry the check to printing position and to return it thereafter to a position without the casing where it may be conveniently removed from the machine. The table is provided with means for automatically clamping the work thereto and for protecting the work during the

movement of the table. Means are also provided on the table for automatically applying ink to the type forms brought to printing position previous to every impression for insuring the adequate inking of the type, which is of particular importance in a machine of this character. These and other features are fully disclosed in the following detailed description of the present embodiment of the invention.

The numeral 10 designates a supporting frame and casing for the machine of substantially rectangular shape, having a covering plate 11 which is formed near its center with an elevation 12 conforming to the operating parts of the machine. Forwardly of the elevated portion 12 plate 11 extends horizontally to the front of the frame 10, thus forming an operating board 13 provided with means for the selection and adjustment of the type forms. This board 13 has thereon a plurality of dials, one of which is indicated at 14, each having markings representing a consecutive series 25 of amounts. The board 13 is also provided with a view aperture 15 through which are visible characters representing the type forms in printing position, as will be presently understood.

The type forms are preferably carried on a plurality of supporting members or bars 16 to 21 inclusive, (Figs. 1 and 3) each bar having fixed on its lower surface a plurality of forms adapted for printing a consecutive series 35 of amounts of convenient range shown by the markings of the corresponding dial, as indicated in Fig. 1. The type forms are arranged in parallel relation transversely of each bar, as shown at 22, (Fig. 2) and each 40 bar has formed upon its upper surface a series of indicating characters 23 (Figs. 1 and 2) each of which corresponds to a type form on the under side of the bar, and these indicating characters are so arranged that 45 when a given type form is brought to printing position by a linear sliding movement of its supporting bar the corresponding indicating character is visible at the aperture 15.

Each series of type forms includes some arbitrary conventional character, as, for instance, the stars shown in Fig. 1, and these type forms are in printing position on any bar which is not employed in the printing 55 of an amount. Type supporting member 16 bears in addition to the conventional character described a series of types for printing "One cent" to "Thirteen cents" inclusive, and also bears the legend "Cents." Type 60 supporting member 17 carries types for printing the series of words "Fourteen" to "Nineteen" inclusive, and the series of multiples of "ten" from "Twenty" to "Ninety" inclusive. The member 18 bears types for 65 printing the series of legends "One dollar"

to "Thirteen dollars" inclusive, and also the legend "Dollars." Member 19 bears types for printing the series of amounts "Fourteen" to "Nineteen" inclusive, and also the series of multiples of "ten" from "Twenty" 70 to "Ninety" inclusive, and also the legend "Dollars." Member 20 bears types for printing the multiples of "one hundred" from "One hundred" to "Nine hundred" inclusive, and also the legend "Dollars." 75 Member 21 bears the multiples of "one thousand" from "One thousand" to "Nine thousand" inclusive. It will be understood that these types are sufficient for selective combination to print any amount in dollars and 80 cents less than ten thousand dollars, and by an extension of the same arrangement, of course, the machine may be constructed for printing amounts of any size desired.

The type supporting members are arranged to be moved in straight lines in a horizontal plane for the purpose of placing any desired type form in printing position and any means may be employed of course for adjustably supporting these type members, or bars. In the present instance the casing of the machine is provided with supporting brackets 26 and 27 at the rear and front of the machine, respectively, in which are fixed the ends of a plurality of guide 85 rods 28. The type bars are arranged side by side with adjacent sides in contact, and the sides of each bar are provided with recesses adapted to slidably engage the bars 28, one of the latter being placed between 100 each pair of type bars, and also on the outside of the bars 16 and 21. Each type bar is provided on its forward upper side with an operating finger piece 29 extending upwardly through a slot in the operating 105 board 13. By moving the finger piece 29 on any bar opposite a character on its dial 14 the corresponding type form is brought to printing position and the corresponding character is indicated at the view aperture 110 15, so that the line of type set up in printing position may be quickly scanned through the aperture 15.

The platen mechanism for impressing the paper against the type comprises preferably 115 an elongated bar 30 having on its upper side an impression surface of sufficient length to coöperate with all of the type forms that may be brought to printing position, and of such width as to coöperate with 120 but one line of types at a time. The impression surface of the types and of the platen may be corrugated or otherwise formed for the purpose of breaking the fiber of the paper during the printing impression in order that the ink may impregnate the paper as disclosed in U. S. Letters Patent 793249 to L. M. Todd, granted June 27, 1905. The platen bar is attached at 125 either end by means of screws 31 to a sup- 130

porting link 32 which has its other end pivotally supported at 33 on a lug 34 on the casing. The platen is thus supported so that it may be reciprocated in a substantially vertical direction toward and from printing contact with the type forms above, and the means for effecting such movement of the platen comprises preferably a link 35 at each end of the platen and pivotally attached thereto at 36, the upper ends of said links 35 being pivotally attached at 37 to rearwardly extending arms 38 on a pair of plates 39, one at either side of the machine. Each plate 39 is pivotally supported on a part 40 extending inwardly from the side wall of the casing, and these plates are integrally connected by a cross piece 41 extending across the machine which also serves as a means for the attachment of an operating member, or handle, 42. Each plate 39 has a downwardly extending branch 43 to which is attached one end of a spring 44, the other end of which is attached at 45 to a part later to be described. Rigidly fixed at each end to the parts 40 projecting inwardly from the sides of the casing frame is a bridge 45^a extending across the type supporting members above the printing position. The purpose of this bridge is to support the type bars during the printing impression.

The means for insuring accurate adjustment of the type forms and for locking them in position during the impression may be of any suitable construction, and for this purpose in the present instance there is pivoted on each side wall of the casing, as indicated at 46, (Fig. 4) an arm 47, these arms being integrally united by a bridge 48 provided at its forward edge with downwardly extending pointed blades 49 (Figs. 3 and 4), these blades being adapted to accurately fit within recesses 50 provided between the indicating characters 23 on the upper side of each type bar. One of these recesses is provided for each type form on the type bar and is so arranged relatively thereto that when the recess is engaged by one of the blades 49 the corresponding type form is accurately centered in printing position, the beveled surfaces of the recesses and the blades serving after the type bar is approximately adjusted by hand to complete the adjustment by drawing the bar precisely into printing position. The means for actuating the centering blades 49 comprises a pin 51 carried by a forwardly extending branch 52 of the arm 47, which pin is adapted to travel in a cam slot 53 in the side plate 39 during the movement of the operating handle 42. Slots 53 are eccentrically arranged with respect to the pivot points of the side plates 39 so that when the latter are rotated about their pivots 40 to raise the platen the centering blades

49 are moved toward the type bars and engaged within recesses 50 to center the type bars, just previous to the contact therewith of the platen.

The means for receiving the work to be printed comprises, preferably, a horizontal table 54 normally projecting forwardly from and adapted to slide through a slot 54^a between the front of the casing and the keyboard 13. This table is provided adjacent its four corners with depending standards or legs 55, each of which has a forked lower end 56 slidably bearing upon guide rods 57 fixed at their ends in the casing, so that the table is supported for a reciprocating movement in a horizontal plane backwardly and forwardly from the front of the machine. For the purpose of protecting the work and clamping it upon the table there is provided, preferably, a cover plate 58 movably attached at its rear edge 59 to the table and carrying at its forward portion on either side a depending lug 60 (Fig. 2), a spring 60^a being interposed between a shoulder on the lug and the table to urge the plate against the table to clamp the work placed therebetween. As the table 54 moves to its forward position, lug 60 engages a cam 61 fixed on the casing which raises the lug and the cover plate 58, a roller 61^a being provided on the casing in position to engage the edge of the table and prevent it from rising, whereby the table and cover plate are separated to receive the work. As the table is moved rearwardly, the lug 60, moving off the cam 61, permits the plate 58 to engage and hold the work upon the table. The actuating means for securing the reciprocating movement of the table include preferably springs 44, each of which is connected at its forward end 45 with the corresponding leg 55 of the table, the rear end of the spring, as previously described, being connected with the actuating side plate 39. Each spring 44 is supported upon an extensible core comprising a plunger 44^a pivoted to the plate 39, and a socket 44^b connected to the table leg so that after the table has been drawn rearwardly by the movement of plate 39 and tension of spring 44, the return movement of the plate 39 seats plunger 44^a in the socket member 44^b and by means of these parts pushes the table back to its forward position. These parts are so arranged that as the handle 42 begins to move forwardly, the table, by means of the springs 44, is drawn rearwardly and continues to be moved by the movement of the handle 42 until the forward legs of the table strike pins 57^a in the guide rods 57, when the movement of the table is arrested. This contact with the pins 57^a occurs before the platen is raised against the work, and the yielding of springs 44 allows of the con-

tinued movement of the operating handle and the platen after the table is stopped in the manner described, to permit the platen to be brought into full contact with the type. Referring to Figs. 4 and 5 it will be seen that the table 54 and plate 58 are provided with apertures 62 and 63, respectively, to permit the platen to be raised therethrough to project the work slightly above plate 58 for engagement with the types, plate 58 thus serving to guard the work against contact with the type forms adjacent those in printing position.

In order that the work may be displaced as little as possible, above the table 54, means are provided for raising the latter and the protecting plate 58 into proximity to the type forms during the printing impression, comprising a pair of cross arms 64 (Fig. 2) one adjacent either end of the platen bar, each cross arm being provided at its ends with an adjustable screw 65 adapted, as the platen is raised, to engage the under side of the table and raise the latter slightly toward the type forms. The screws 65 are so adjusted that the table is not raised high enough to bring the plate 58 into actual contact with the type forms. Means are preferably provided for urging the table downwardly again after the impression and thus stripping the work from the type comprising rollers 66 journaled at the lower ends of a pair of members 67 which are supported for sliding movement by the bridge 45^a, springs 68 being provided for urging the rollers 66 into engagement with the table at its sides.

The inking means is preferably of such a construction that the types selected for printing will be freshly inked previous to each impression to insure the application to the work of an adequate supply of ink, so that the latter will thoroughly impregnate the work and thus serve to form an indelible impression. To this end the table 54 is provided at each of its sides with a depending bracket 69 having at its rear end an inclined slot 70 within which is journaled the end of a spindle 71 carrying the ink rolls 72. The spring 73 at one end is attached at 74 to the bracket 69 and at its other end to the end of the spindle 71 so as normally to move the spindle upwardly in the slots 70 and thus carry the inking rolls forwardly and upwardly against the type forms. It is only necessary, however, to ink those type forms which have been placed in printing position, and means are therefore provided for controlling the contact of the inking rolls with the type forms comprising a bent lever 75 pivotally supported at 74 on each of the brackets 69. Each lever 75 bears downwardly upon an end of the spindle 71 and carries at its forward end a pin 76 engaging beneath a cam surface 77 supported

in fixed position on the casing. The parts are so arranged that the levers 75 press the spindle 71 downwardly in its bearings so as to normally hold the ink rolls out of contact with the type forms, but the cam 70 surfaces 77 are provided with concave portions 78 of such shape and position that as the table is moved rearwardly in the manner described, the pins 76 pass into the concave portions 78 of cams 77 as the inking rolls 75 approach the type forms in printing position and thereby permit springs 73 to raise the ink roll upwardly into rolling contact with the type forms, an opening 54^b being provided in the table for the passage of the 80 ink roll therethrough.

Means are provided for gaging the location of the work on the table 54 in such position that the impression will be made on the line of the work intended for it, comprising a gage member 79 adjustable over a scale 80 on the table, the member 79 having a portion projecting slightly above the table at 81 against which the rear edge of the work is placed. This gage, however, may 90 be of any desired construction and forms no part of the present invention.

The operation of the machine is briefly as follows: The type bars having been adjusted to bring the desired type to printing position, as indicated at the view aperture 15, the work is placed upon the table 54 beneath the cover plate 58, and handle 42 is pulled forwardly, thereby moving the work table rearwardly. This movement of 100 the table carries the inking rolls into engagement with the types selected for printing and places the work in proper position to receive the impression. At the same time, the centering device accurately centers the 105 type forms and locks them in printing position. The platen is raised, and after the table reaches the position described, the platen carries the work against the types above. Handle 42 is then returned to its 110 rear position, thereby retracting the platen and the centering device and returning the work table to normal position with its forward portion projecting through the front of the casing so that the work may be conveniently removed from the table.

Having thus described my invention, what I claim as new, and desire to secure by Letters Patent is:—

1. In a printing apparatus, a casing provided with a substantially horizontal slot; a plurality of type supporting members above the slot each provided with a plurality of types and being movable to bring said types selectively to printing position; a 120 platen below said slot and movable toward and from said types to impress the work; a table normally in position to have the work placed thereon and being movable to carry the work through said slot to printing posi- 130

- tion between the types and platen; spring actuated means for automatically engaging the work and clamping it on the table during the movement of the latter; and operating means for effecting said movement of the platen to produce an impression. 70
2. In a printing apparatus, a casing provided with a substantially horizontal slot; a plurality of slides supported by said casing above the slot, each slide being provided with a plurality of types and being movable to bring said types, selectively, to printing position; a platen below the slot and movable toward and from said types to impress the work; a table normally in position to have the work placed thereon and being movable to carry the work through said slot to printing position between the types and platen; means whereby movement of said table away from normal position will automatically clamp the work on the table; and common operating means for effecting said movement of the table and actuating the platen to produce an impression. 75
- 15 3. In a printing apparatus, the combination with a platen, of type carrying means adjustable to set different type forms at a printing line opposite said platen, means for effecting relative movement of the type carrying means and platen to print, a work carriage movable to carry the work to and from a position between the type and platen, an ink applying device carried by the carriage and cam controlled means for moving the ink applying device relative to the carriage into contact with the type at the printing line as the device is carried past said line. 80
- 20 4. In a printing apparatus, the combination with a platen, of a set of type carriers adjustable to position desired type forms at a printing line opposite the platen, means for bringing the type carriers and platen together to print, a work carriage movable to carry the work to and from a position between the type and platen, an ink applying device relative to the carriage mounted on the carriage and means for moving the ink applying device in and out of contact with the type at the printing line as the device is carried past said line. 85
- 25 5. In a printing apparatus, a plurality of type supporting members each movable to bring various types, selectively, to printing position; a platen for coöperation with said types, said platen and types having a relative movement to impress the work; a reciprocating carrier adapted to have the work placed thereon and to move it to and from printing position; an operating member having a printing movement to effect said relative movement of the types and platen; actuating means for automatically reciprocating said carrier by said printing movement of the operating member; an inking element movably supported on the carrier and adapt- 90
- ed to be moved across the types by the movement of the carrier; and means coöperating with said element to move the latter relative to the carrier into inking contact with the types in printing position. 95
6. In a printing apparatus, a plurality of type supporting bars having a linear longitudinal sliding movement to bring various type forms on each bar selectively to printing position; a platen movable toward and from the selected type forms to press the work thereagainst; a work carrier having a reciprocating movement to carry the work to and from printing position; an operating member having a printing movement to effect said movement of the platen; actuating means for automatically reciprocating said carrier by said printing movement of the operating member, and means controlled by said actuating means for automatically 100 clamping the work to the work carrier. 105
7. In a printing apparatus, a plurality of type supporting bars having a linear longitudinal sliding movement to bring various type forms on each bar selectively to printing position; a platen movable toward and from the selected type forms to press the work thereagainst; a work carrier having a reciprocating movement to carry the work to and from printing position; an operating member having a printing movement to effect said movement of the platen; work clamping means actuated automatically by the printing movement of said operating member; and actuating means for automatically reciprocating said carrier by said printing movement of the operating member. 110
8. In a printing apparatus, a platen; a plurality of type supporting bars having a longitudinal sliding movement to bring various type forms on each bar, selectively, to position for coaction with the platen; operating means having an impressing movement to effect relative approach and separation of the selected type and platen; a work carriage reciprocated automatically to and from printing position by said impressing movement of the operating means; and work clamping means operated automatically by 115 the reciprocating movement of the carriage. 120
9. In a printing apparatus, a platen; a plurality of type supporting bars having a longitudinal sliding movement to bring various type forms on each bar selectively to position for coaction with the platen; operating means having an impressing movement to effect relative approach and separation of the selected type and platen; a work carriage reciprocated automatically to and from printing position by the impressing movement of said operating means; an inking element carried by the carriage and movable relative to said carriage and means for moving the inking element relative to the 125 130

- carriage as the element passes the selected type forms whereby to ink said forms.
10. In a printing apparatus, a platen; a plurality of type supporting members movable to bring various type forms on each selectively to position for coaction with the platen; operating means having an impressing movement to move said platen toward and from the selected type forms; a work carriage having a movement to and from printing position adjacent the selected type and platen, and also a movement while in printing position in common with the platen toward and from the selected type forms; and actuating means operated automatically by said impressing movement of the operating means for effecting each of said movements of the carriage.
11. In a printing apparatus, the combination with a printing couple, of an operating means for actuating the printing couple, a work carriage and connections for actuating the carriage to carry the work in and out of position between the printing couple and means controlled by the operating member for automatically clamping the work to the work carriage.
12. In a machine of the class described, the combination with the members of a printing couple, of means for bringing said members together to effect printing, a work carriage movable to carry the work to and from a printing position between the members of the couple and also movable when in that position to carry the work toward and from one of the members, and devices for effecting said movements of the carriage at operations of the aforesaid means.
13. In a machine of the class described, the combination with a printing couple, one member of which is movable toward and from the other to effect printing, of means for effecting said movement, a work carriage movable to carry the work to and from a position between the members of the couple and then toward and from the stationary member of the couple whereby to carry the work into proximity to said member, and devices for effecting said movements at operations of the aforesaid means. 50
14. In a machine of the class described, the combination with a platen, of type supporting means adjustable to set different type forms at a printing line opposite the platen, operating devices for effecting relative movement of the type supporting means and platen to print, a work carriage normally in position to have the work placed thereon and movable first to carry the work between the type and platen then toward 60 and from the type and then back to the normal position, mechanism whereby said movements of the carriage are effected at operations of the aforesaid operating device, and automatically operated mechanism for clamping 65 the work to the carriage while the carriage is away from its normal position.

It is hereby certified that in Letters Patent No. 1,335,207, granted March 30, 1920, upon the application of Libanus M. Todd, of Rochester, New York, for an improvement in "Check-Protectors," errors appear in the printed specification requiring correction as follows: Page 5, line 46, claim 4, strike out the words "relative to the carriage;" same page and claim, line 48, after the word "device" insert the words *relative to the carriage*; and that the said Letters Patent should be read with these corrections therein that the same may conform to the record of the case in the Patent Office.

Signed and sealed this 11th day of May, A. D., 1920.

[SEAL.]

M. H. COULSTON,

Acting Commissioner of Patents.
